[57] CLAIM

The ornamental design for a toy hoop roller, as shown and described.

DESCRIPTION

FIG. 1 is a side elevational view of a toy hoop roller showing my new design, the side opposite being substantially a mirror image thereof;

FIG. 2 is a rear elevational view thereof;

FIG. 3 is a front elevational view thereof;

FIG. 4 is a top plan view thereof, and;

FIG. 5 is a bottom plan view thereof.
